Specification for Design.

Patented Aug. 2, 1921.

Application filed April 18, 1921. Serial No. 462,451. Term of patent 14 years.

To all whom it may concern:

Be it known that I, THEODORE E. CRECELIUS, a citizen of the United States, residing at the city of St. Louis, State of Missouri, have invented a certain new, original, and ornamental Design for a Gum-Package-Dispensing Receptacle or Similar Article, of which the following is a specification, reference being had to the accompanying drawing, forming a part thereof.

The drawing illustrates in perspective a gum-package dispensing receptacle or other article embodying my new design.

My new design for a gum-package dispensing receptacle or similar article comprises pairs of spaced upstanding legs or standard A—A and B—B supporting therebetween a series of obliquely disposed commodity-trays or chutes C artistically arranged in superposed spaced relation, the entire series of trays being topped by a covering panel D.

I claim:

The ornamental design for a gum-package dispensing receptacle or similar article substantially as shown and described.

THEODORE E. CRECELIUS.
